Primary Examiner — Philip S Hyder(74) *Attorney, Agent, or Firm* — Birchwood IP(57) **CLAIM**

The ornamental design for a mechanical rasp, as shown and described.

DESCRIPTION

FIG. 1 is a front, top, and right side perspective view of a mechanical rasp, showing our new design;
 FIG. 2 is a front view thereof;
 FIG. 3 is a rear view thereof;
 FIG. 4 is a left side view thereof;
 FIG. 5 is a right side view thereof;
 FIG. 6 is a top plan view thereof;
 FIG. 7 is a bottom plan view thereof; and,
 FIG. 8 is an enlarged perspective view of the portion of the mechanical rasp circled in FIG. 1.
